United States Patent Office

Des. 194,479
Patented Jan. 29, 1963

194,479

LUMINAIRE

Myron F. Pettengill, Hendersonville, N.C., assignor to
General Electric Company, a corporation of New York

Filed Dec. 5, 1961, Ser. No. 67,807

Term of patent 14 years

(Cl. D48—31)

FIG. 1 is a perspective view of a luminaire showing
my new design;

FIG. 2 is a top plan view;

FIG. 3 is a bottom plan view; and

FIG. 4 is a side elevational view thereof.

I claim:

The ornamental design for a luminaire as shown.
